ATTY.

UNITED STATES PATENT OFFICE.

HAROLD THOMAS PRATT AND EDWARD COLEGATE WEST, OF OTTAWA, ONTARIO,
CANADA.

DESIGN FOR A TOY AEROPLANE.

54,768.

Specification for Design.

Patented Mar. 23, 1920.

Application filed May 22, 1919. Serial No. 299,027. Term of patent 7 years.

To all whom it may concern:

Be it known that we, HAROLD THOMAS PRATT and EDWARD COLEGATE WEST, subjects of the King of Great Britain, and residents of the city of Ottawa, in the Province of Ontario, Dominion of Canada, have invented a new, original, and ornamental Design for Toy Aeroplanes, of which the following is a specification, reference being had to the accompanying drawings, forming part thereof, which represents a perspective view of a toy aeroplane embodying my new design.

We claim—

The ornamental design for a toy aeroplane, as shown.

Signed at Ottawa, in the Province of Ontario, Dominion of Canada, this 10th day of May, 1919.

HAROLD THOMAS PRATT.
EDWARD COLEGATE WEST.

Witness:

JAMES MITCHELL.
